Frank C. Curtis
Attorney

UNITED STATES PATENT OFFICE.

HOWARD E. WILLIAMS, OF ROUND LAKE, NEW YORK, ASSIGNOR TO BILTRITE COLLAR COMPANY, A PARTNERSHIP COMPOSED OF HARRY COHEN AND CHARLES COHEN, OF NEW YORK, N. Y.

FOLD COLLAR.

Application filed August 30, 1926. Serial No. 132,467.

Reference may be had to the accompanying drawings, and the reference characters marked thereon, which form a part of this specification. Similar characters refer to 5 similar parts in the several figures therein.

The principal object of the invention is to improve the set and appearance of a soft or semi-soft fold-collar in use.

Other objects will appear in connection 10 with the following description.

Fig. 1 of the drawings is a front view in perspective of a fold-collar made in accordance with my invention in substantially the form assumed by the collar in use.

Fig. 2 is a vertical cross section of the same taken on the broken line 2—2 in Fig. 1.

Fig. 3 is a similar section showing a modification.

The collar includes a band, 1, and a fold- 20 over top, 2.

In Fig. 2, I have shown the band made up of three plies or thicknesses of fabric,— an inner ply, 3, an outer ply, 4, and an intermediate or interlining ply, 5; and the 25 fold-over top made up of two plies or thicknesses of fabric,—an inner ply, 6, and an outer ply, 7.

In making the collar in accordance with 30 my invention, I form the inner ply, 3, of the band and the outer ply, 7, of the fold-over top of the same integral piece of fabric, as shown in Fig. 2.

I have also shown the outer ply, 4, of the band and the inner ply, 6, of the fold-over 35 top made of the same integral piece of fabric; but if desired they may be made of separate pieces of fabric in any known manner.

The plies of the band are turned along 40 their outer edges and secured together by stitching, 8.

The plies of the fold-over top are in like manner turned along their outer edges and secured together by stitching, 9.

The intermediate ply, 5, of the band has a binding, 13, along its inner or upper edge and is secured along said edge adjacent to the fold-line of the collar by stitching, 10, to the outer ply, 4, only of the band. It 50 will be observed that the binding is disposed along the fold line (Fig. 2) and entirely within the band so as to mark the collar fold and reinforce at the fold the outer ply of the fold-over top and the inner ply of the

band, which in the present instance are integral. Obviously, this fold marking and reinforcing strip 13 may be carried upon the intermediate ply or interlining in various ways, but it is desirable that it be upon the interlining, since it is thereby supported principally by the interlining, and furthermore, when arranged in the specific manner illustrated, protects the adjacent plies from the edge of the interlining.

It will be observed that the binder 13 is secured to the interliner by the stitching 10 in such a way that its folded portion is spaced from the edge of the interliner, whereby to give a soft collar edge at the fold and a more rounded effect, which greatly improves the appearance of the collar. The construction and arrangement of the strip 13 insures that the collar will fold accurately, and while giving the proper rigidity at the fold, at the same time affords a soft edge.

The integral piece or body of fabric which forms the inner ply, 3, of the band and the outer ply, 7, of the fold-over top is disconnected or free from the other plies of the top and band preferably from the edge stitching, 8, of the band, to the edge stitching, 9, of the top, and particularly along and adjacent to the fold-line of the collar.

By thus having the integral member forming the inner band-ply, 3, and the outer fold-over top ply, 7, of the band free from connection with the other plies of the collar along the fold-line of the collar, when the collar is folded and bent to curved form as in use, this integral member is permitted more or less freedom of movement independently of the other plies of the collar in assuming the curvilinear set which is desirable in use; and the tendency of the outer ply of the fold-over top to wrinkle or buckle 90 when forced to assume the curvilinear set is practically eliminated.

The freedom for self-adjustment of the inner ply, 3, of the band and the outer ply, 7, of the fold-over top which is permitted by reason of my invention frees these plies from the restraining influence of the other plies along the longitudinal middle of the collar when ironed out flat before the collar is folded.

While the advantages due to my invention are most marked in a soft or semi-soft fold-over collar, certain of said advantages render

the invention also applicable to stiff or fully starched fold-collars.

In Fig. 3, I have shown an integral interlining ply, 11, extending throughout both the band and the folded-over top.

When such an interlining ply is employed, I prefer to secure the upper edge of the interlining ply, 5, of the band by stitching, 12, to said integral interlining ply, 11, only 10 as shown, thus leaving both continuous or integral members which form respectively the inner ply of the band and the outer ply of the fold-over top, and the outer ply of the band and the inner ply of the fold-over top, 15 free from each other and from the interlining plies along and adjacent to the fold-line of the collar.

What I claim as new and desire to secure by Letters Patent is:

- 20 1. A fold collar having a fold-over top formed of a plurality of plies of fabric, and a band formed of at least three plies of fabric including an intermediate ply limited to the band only, said intermediate ply having 25 a fold marking and reinforcing strip along the fold line of the collar, the strip being folded upon itself within the band whereby to provide a rounded marker and reinforce, the inner ply of the band and the 30 outer ply of the fold-over top being formed of an integral piece of fabric free from the other plies of the collar along and adjacent to the fold line of the collar and folded over said marking and reinforcing strip and supported by the latter along the fold, said band intermediate ply being substantially co-extensive with the reinforcing strip and the fold.
- 40 2. A fold collar having a fold-over top 45 formed of a plurality of plies of fabric, and a band formed of at least three plies of fabric including an intermediate ply limited to the band only and carrying a fold marking and reinforcing strip along the fold line, the inner ply of the band and the outer ply of the fold-over top being formed of an integral piece of fabric free from the other plies of the collar along and adjacent to the fold line of the collar, said fold marking and reinforcing strip being disposed entirely 50 within the plane of the band and binding the edge of the intermediate ply, whereby to protect the adjacent plies of the collar and provide a rounded fold reinforce, the said integral piece of fabric being folded over said reinforcing strip and supported by the latter at the fold, and said intermediate band ply being substantially co-extensive with the fold.
- 60 3. A fold collar having a fold-over top 65 formed of a plurality of plies of fabric, and a band formed of at least three plies of fabric substantially co-extensive throughout the band including an intermediate ply limited to the band only and carrying at its edge

along the fold line a fold marking and reinforcing strip, the inner ply of the band and the outer ply of the fold-over top being formed of an integral piece of fabric free from the other plies of the collar along and adjacent to the fold line of the collar, the outer ply of the band and the inner ply of the fold-over top being formed of an integral piece of fabric free from the other plies of the collar along and adjacent to the fold line of the collar, said fold marking and reinforcing strip binding said edge of the intermediate ply and being folded upon itself within the plane of the band.

4. A fold collar having a fold-over top 80 and a band and including two outside plies and an interlining ply each extending substantially throughout both the band and the fold-over top, and free from the others along and adjacent to the fold line of the 85 collar, and another interlining ply limited to the band only and secured along its upper edge to the other interlining ply only.

5. A fold collar having a fold-over top 90 and a band and including two outside plies and an interlining ply each extending substantially throughout both the band and the fold-over top, and free from the others along and adjacent to the fold line of the collar, another interlining ply limited to the band 95 only and secured along its upper edge to the other interlining ply only, and a fold marking and reinforcing strip on said last mentioned interlining ply along the fold line.

6. A fold collar having a fold-over top 100 and a band and including two outside plies and an interlining ply each extending substantially throughout both the band and the fold-over top, and free from the others along and adjacent to the fold line of the 105 collar, another interlining ply limited to the band only and secured adjacent its upper edge to the other interlining ply only, and a fold marking and reinforcing strip carried by said last mentioned interlining ply along 110 the fold line and binding the edge of the ply.

7. A fold collar having a fold-over top 115 formed of a plurality of plies of fabric, and a band formed of at least three plies of fabric including an intermediate ply limited to the band only, and substantially co-extensive therewith, said intermediate ply having an edge adjacent the collar fold line and substantially paralleling the same, the outer ply of the fold-over top being formed of a piece of fabric which extends over said fold to the band, and a fold marking and reinforcing strip beneath said outer ply folded upon itself within the band and carried by said band intermediate ply.

8. A fold collar having a fold-over top 125 formed of a plurality of plies of fabric, and a band formed of at least three plies of fabric including an intermediate ply limited to the band only, and substantially co-ex-

tensive therewith, said intermediate ply having an edge adjacent the collar fold line and substantially paralleling the same, the outer 5
ply of the fold-over top being formed of a piece of fabric which extends over said fold to the band, and a fold marking and reinforcing strip beneath said outer ply carried by said band intermediate ply, said strip being folded upon itself within the band and 10
binding and enveloping by receiving between its folds the edge of the intermediate ply.
9. A fold collar having a fold-over top formed of a plurality of plies of fabric, and a band formed of at least three plies of fabric 15
including an intermediate ply limited to the band only, and substantially co-extensive therewith, said intermediate ply having an edge adjacent the collar fold line and substantially paralleling the same, the outer 20
ply of the fold-over top being formed of a piece of fabric which extends over said fold to the band, and a fold marking and reinforcing strip beneath said outer ply carried by said band intermediate ply, said strip being 25
folded upon itself within the band and serving to bind and envelope the edge of the intermediate ply and having its interme-

diate portion folded over the edge of the ply spaced therefrom whereby to provide a soft rounded fold reinforce. 30

10. A fold collar having a fold-over top formed of a plurality of plies of fabric, and a band formed of at least three plies of fabric including an intermediate ply limited to the band only and carrying a fold marking and 35
reinforcing member along the fold line, the inner ply of the band and the outer ply of the fold-over top being formed of an integral piece of fabric free from the other plies of the collar along and adjacent to the fold line 40
of the collar, said fold marking and reinforcing member being disposed entirely within the plane of the band and binding the edge of the intermediate ply, whereby to 45
protect the adjacent plies of the collar and provide a rounded fold reinforce, the said integral piece of fabric being folded over said reinforcing member and supported by the latter at the fold, and said intermediate band ply being substantially co-extensive 50
with the fold.

In testimony whereof, I have hereunto set my hand this 14th day of August, 1926.

HOWARD E. WILLIAMS.
